FIG.3

Des. 201,568

PAGE 4

FIG. 4

FIG. 5

FIG. 1 is a front perspective view taken from one side of a gasoline pump housing embodying my new design;

FIG. 2 is a rear elevational view thereof;

FIG. 3 is an elevational view taken from the side opposite that shown in FIG. 1;

FIG. 4 is a side elevational view of a modified form of the gasoline pump housing shown in FIGS. 1 through 4, the modified form differing therefrom only in the direction of the taper of the lower portion thereof; and

FIG. 5 is a rear elevational view of FIG. 4.

The dominant features of my design reside in the portions shown in the full lines.

I claim:

The ornamental design for a gasoline pump housing, substantially as shown and described.
